J. A. B. SMITH

TYPEWRITING MACHINE

Filed April 28, 1920

FIG. 1.

FIG. 2.

FIG. 3.

INVENTOR:

Jesse A. B. Smith
BY *B. B. Stickney*
ATTORNEY.

UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed April 28, 1920. Serial No. 377,189.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to typewriting machines, and is herein disclosed as applied to an Underwood standard typewriting machine of the fan-fold or continuous billing variety shown in the patent to Wernery and Smith, No. 1,132,055, dated March 16, 1915.

The work-sheets for such machines are usually in the form of webs fan-folded together, and the forms typed thereon are severed. In such machines it is sometimes desired to utilize narrow webs for the original entry, while the other webs or some of them may be wider to accommodate data not shown upon the original. It is also frequently desirable to slit the web or webs automatically along the fan-folded edges, so that the manifolded typed forms are separated laterally from one another.

One feature of the present invention provides a wide side gaging device for the wide webs, and a side gaging device for the narrow webs, so that the webs will be properly aligned relatively to each other, so that the inner forms may be properly filled out as carbon copies of the outer forms, even if the different widths of web are drawn from separate sources of supply.

The improvement for severing the webs along their folds is in the nature of flat sharp-edged tongues or extensions of the usual thin carbon-clip blades projecting at such a special angle that as the web is drawn forward, the angular extensions easily slit the fold, which is usually perforated to facilitate such slitting without liability of tearing or fouling the paper. By utilizing carbon-clip blades of varying lengths according to the width of web used, the sharp thin blades will be found to have comparatively little tendency to shift the webs out of alignment sidewise relatively to each other in slitting, if the gages are properly adjusted.

It has been customary to attach an angularly projecting wire to the end of the carbon blade, and to use the wire for slitting the paper, making it necessary to fit up each

blade, often cutting off a piece of the blade 55 to render it of the desired length. In practicing this invention, a supply of the elbow-blades of different lengths may be kept in stock and readily applied to any machine as required.

Other features and advantages will hereinafter appear.

In the accompanying drawings,

Figure 1 is a diagrammatic, fragmentary, perspective view, taken from the rear, of a 65 machine of the kind referred to, many parts being omitted, and showing the two widths of web passing beneath the platen.

Figure 2 is a plan view of the carbon-paper-carriage, with the webs threaded 70 therethrough.

Figure 3 is a front view of the parts seen in Figure 2.

Broad webs, 1, 2 and 3, which may be fan-folded, are drawn from the rear over the 75 cross-bar, not shown, of an extension 4 of the typewriter carriage, of which the body is not shown, and pass beneath the platen 5. The fan-folded webs 1, 2 and 3 are threaded between the carbon-clip-bars 6 and 7 of a 80 carbon-paper-carriage, having a detachable top 8 on which the carbon-clip-bars 6 and 7 are detachably mounted. The clip-bars 6 and 7 are offset from each other vertically and rearwardly, being, for this purpose, 85 mounted upon the opposite steps of bases 9 and 10 provided with the usual openings 11 for detachably holding the clip-bars.

Each clip-bar 6 and 7 is usually provided with a clip 12 pivoted by a pin 13 upon its 90 bar, so that carbon-sheets held by the clips 12 extend between the webs 1 and 2 and the webs 2 and 3.

According to the present invention, there may also be passed around the platen 5, and 95 shown herein as outside the webs 1, 2 and 3, a narrow web or a set of webs 14, 15, 16 and 17. These webs are threaded between carbon-clip-bars 18, 19 and 20, which carry 100 clips 12 like the clip-bars 6 and 7, and support carbon-sheets 21 between the thicknesses of web 14, 15, 16 and 17. To enable matter typed upon the outer web 17 to be reproduced upon the outer sheet 3 of the broader web, there is also provided a carbon-clip-bar 22, carrying a carbon-sheet interposed between the web 3 and the web 14, 105 with the result that matter typed upon the

outer web 17 will be reproduced upon all the thicknesses of web.

The wide webs 1, 2 and 3 are held against sidewise shifting by side gages 23 and 24 adjustably held by screw clamps 25 upon the backs of the bases 9 and 10 of the carbon-paper-carriage. To accurately align the narrow webs 14, 15, 16 and 17 relatively to the wider webs, the narrow webs may be 10 gaged against the side gage 23 and have their other edges gaged by a side gage 26 adjustably held by a screw clamp 27 to the top 8 of the carbon-paper-carriage.

To make sure that the narrow webs do not 15 slip off over the top of the side gage 26, said gage is provided with an overhanging extension or lip 28, which overhangs the web 14, etc., far enough to insure that the web never escapes from the gage 26. This holds 20 the webs flat at their folds near where they are slit. The gage 26 may also be provided with a lower lip 29 to hold the bottom web 17 also in place.

In order to slit or cut the folds 1, 2 and 3 25 away from each other, their carbon-clip bars 6 and 7 may be provided with angular extensions 30, which lie angularly across the folds between the webs and are preferably flat and smooth continuations of their respective clip bars, thus holding the webs flat and compact. It is found that the extensions 30 may advantageously have blunt edges only a little thinner than the body of their clip bar proper, so that in case the folding of the webs has been imperfectly done, 35 the webs will be drawn out flat before they are slit.

For severing the narrow webs 14, 15, 16 and 17 from each other, their carbon-clip-bars 40 are provided with similar extensions 30 having the same function and same position relative to the fold of their respective webs. Thus, the flat blade extensions 30 of the carbon-clip-bars tend to hold the webs flat 45 down in place, and confine the narrow webs properly within the gage 26. For convenience, the carbon-clip-bar 22 may be provided with an extension 30 like the other carbon-clip-bars, so that one type of said 50 bars will serve for all purposes. Moreover the fact that the bar 22 has the extension 30 overlying the narrow webs helps to confine those webs in their proper paths. The webs at the printing line upon the platen 5 will 55 all be positively aligned sidewise, since their side gages 23, 24 and 26 align the edges of the webs, and the portions where they are unslit hold the slit portions aligned at the platen.

60 The slitting extensions 30 are usually effective when the webs are gaged after the platen 5 is displaced in the usual manner. This is the time when the webs are brought 65 against the usual leading-edge gage, and the carbon-paper-carriage is pushed rearwardly

by its handle 31, which pushes it rearwardly upon the rails 32 upon which it reciprocates and which form the body of the extension 4.

Variations may be resorted to within the scope of the invention, and portions of the 70 improvements may be used without others.

Having thus described my invention, I claim:

1. A carbon-holder for use in fan-fold typewriting machines, comprising a piece 75 of sheet-metal formed to provide a thin carbon-holding body-portion to which a sheet of carbon may be secured and a thin work-web-cutting blade-portion of the same thickness as the body-portion, extending obliquely from the body-portion at the end thereof, and integral therewith, the construction being such that the combined carbon-holding body and work-web-cutting blade may be made by a single stamping 80 operation.

2. A carbon-holder for use in fan-fold typewriting machines, comprising a piece of thin metal formed to provide a thin carbon-holding body-portion to which carbon may 90 be secured and a thin work-web-cutting blade-portion integral with the body-portion.

3. In a typewriting machine, the combination with a carriage and a platen therein, 95 of an extension of the carriage behind the platen, a carbon-paper carriage reciprocable upon the extension, long carbon-holding blades on the carbon-paper carriage for holding carbons interleaved with the plies 100 of a wide work-web, the blades having web-slitters for slitting the folds of the plies between which they lie, relatively short carbon-holding blades on the carbon-paper carriage for holding carbons interleaved with the plies of a relatively narrow work-web directed to the same field of the platen 105 as the wide work-web, the relatively short carbon-holding blades having web-slitters for slitting the folds of the plies between 110 which they lie, and means for engaging both side edges of both the wide and narrow webs to maintain the webs in operative relation to their respective web-slitters and to their interleaved carbon-sheets and in 115 predetermined relation to each other.

4. In a typewriting machine, the combination with a carriage and a platen therein, of an extension of the carriage behind the platen, a carbon-paper carriage reciprocable upon the extension, carbon-holding blades of equal length extending from one side of the carbon-paper carriage to lie within vertically coinciding folds of wide and narrow superposed fan-fold webs directed 120 to the platen, long carbon-holding blades extending from the opposite side of the carbon-paper carriage to lie within folds of the wide fan-fold web, short carbon-holding blades extending from the second- 125

mentioned side of the carbon-paper carriage to lie within folds of the narrow fan-fold web, web-slitters on all of the carbon-holding blades, means for engaging the coinciding folds of the wide and narrow webs to resist the lateral thrust upon the wide and narrow webs of the slitters carried by the long carbon-blades of equal length, and separate means for engaging the folds of the wide web and the folds of the narrow web to resist, respectively, the lateral thrust of the slitters carried by the long carbon-holding blades and by the short carbon-holding blades, said web-engaging means operating to maintain the webs in operative relation to their respective holders and in predetermined relation to each other.

5. In a typewriting machine, the combination with a carriage and a platen therein, of an extension behind the platen, a carbon-paper carriage reciprocable upon the extension, long carbon-holding blades on the carbon-paper carriage to extend between the folds of a wide fan-fold web to hold carbons interleaved with the plies of the wide fan-fold web, short carbon-holding blades on the carbon-paper carriage to extend between the folds of a narrow fan-fold web to hold carbons interleaved between the plies of the narrow fan-fold web, means for guiding the wide fan-fold web into co-operative relation with the carbons held by the long blades, and means for guiding the narrow fan-fold web into co-operative relation with the carbons held by the short blades, said means co-operating also to maintain the wide and narrow fan-fold webs in predetermined relation to each other.

40 6. In a typewriting machine, the combination with a typewriter carriage and a platen therein, of an extension of the carriage behind the platen, a carbon paper carriage reciprocable upon the extension, a side gage on said carbon paper carriage adapted to gage the side of a web threaded through it, an adjustable side gage on the carbon paper carriage for the other side of the web, a separately adjustable gage for a bottom narrower web on said other side, and an extension of said latter gage adapted to overlie the bottom web.

7. In a typewriting machine, the combination with a typewriter carriage and a platen therein, of an extension of the carriage behind the platen, a carbon paper carriage reciprocable upon the extension, side gages on said carbon paper carriage adapted to

gage the sides of a web threaded through it, a separate side gage for a folded edge of a narrower fan-fold web also carried on the carbon paper carriage and gaged at its other edge by one of the first-mentioned side gages, means for holding the narrower web to said separate gage, and carbon clip bars upon the carbon paper carriage comprising flat angular extensions serving to slit fan-folded webs and hold them flat, said bars being of different lengths to correspond with the positions of the edges where slitting is to be effected.

8. In a typewriting machine, the combination with a typewriter carriage and a platen therein, of an extension of the carriage behind the platen, a carbon paper carriage reciprocable upon the extension, a side gage on said carbon paper carriage adapted to gage the side of a web threaded through it, an adjustable side gage on the carbon paper carriage for the other side of the web, a separately adjustable gage for a folded edge of a bottom narrower folded web on said other side, means for holding the narrower web down on its gage, and carbon clip bars upon the carbon paper carriage comprising flat angular extensions serving to slit fan-folded webs and hold them flat, said bars being of different lengths to correspond with the positions of the edges where slitting of the webs is to be effected by the flat angular extensions.

9. In a typewriting machine, the combination with a typewriter carriage and a platen therein, of an extension of the carriage behind the platen, a carbon paper carriage reciprocable upon the extension, a side gage on said carbon paper carriage adapted to gage the side of a web threaded through it, an adjustable side gage on the carbon paper carriage for the other side of the web, a separately adjustable gage on said other side for a folded edge of a bottom narrower fan-fold web, also gaged by the first mentioned gage, an extension of said latter gage adapted to overlie the bottom web, and carbon clip bars upon the carbon paper carriage comprising flat angular extensions serving to slit fan-folded webs and hold them flat, the carbon clip bars on one side being of uniform length and those on the other side being of two different lengths to correspond to the widths of the two webs.
